UNITED STATES PATENT OFFICE.

EDWARD CLIFF, OF ROCHESTER, NEW YORK.

BOLSTER-SPRING FOR WAGONS.

SPECIFICATION forming part of Letters Patent No. 399,838, dated March 19, 1889.

Application filed May 21, 1888. Serial No. 274,503. (No model.)

To all whom it may concern:

Be it known that I, EDWARD CLIFF, of Rochester, in the county of Monroe, in the State of New York, have invented new and useful Improvements in Bolster-Springs for Vehicles, of which the following, taken in connection with the accompanying drawings, is a full, clear, and exact description.

This invention relates to the same class of bolster-springs in which are included the springs shown in my patents, Nos. 376,857 and 382,137, dated, respectively, January 24, 1888, and May 1, 1888.

My present invention consists in a simpler construction of the spring and means for securing the same to the bolster and body-supporting cross-bar; and the invention also consists in improved devices connected to the said cross-bar for affording better bearings for the same on the body of the vehicle and more effectually preventing the cross-bar from tilting, all as hereinafter more fully described, and specifically set forth in the claims.

In the annexed drawings, Figures 1 and 2 are top plan views of bolster-springs embodying my improvements. Fig. 3 is a side view of the same with the body-supporting bar mounted on the spring. Fig. 4 is an inverted plan view of a section of the vehicle-body, showing the position of the body-supporting bar. Fig. 5 is an inverted plan view of the shoe or plate attached to the end of the body-supporting bar. Fig. 6 is a vertical transverse section on line $x-x$, Fig. 5; and Fig. 7 is a transverse section on line $y-y$, Fig. 1.

Similar letters of reference indicate corresponding parts.

B represents the bolster; A, the body of the vehicle, and C the body-supporting cross-bar, which is supported by springs interposed between it and the bolster at or near the ends thereof. Each of said springs I form of two separate coils, D D, disposed axially vertically at opposite sides of the bolster and supported at their bases on said bolster, and having their upper ends underneath the body-supporting cross-bar C and rigidly secured thereto. The attachment of said coil-springs I prefer to make in the following manner: Across the top of the bolster I place a hanger, a, which projects at opposite sides of the bolster

and is formed with eyes a' a' , standing with their planes vertically and at right angles to the sides of the bolster and abutting against the same, so as to sustain the hanger laterally. 55

Each of the coil-springs D is formed individually at its base with an eye, b, which stands with its plane vertically and parallel with the side of the bolster and is linked in one of the eyes a' , and thus affords an oscillatory support for the spring, such support being essential to obviate torsion of the spring when subjected to a load. The upper end of each coil D is formed individually with an eye, c, which stands with its plane horizontally 65 underneath the body-supporting cross-bar C, to which it is rigidly attached by bolts $l l$, passing through said eyes and through the said cross-bar at opposite sides of the longitudinal central line of the latter. 70

To the under side of the body A of lumber-wagons are usually attached transversely two cleats, $h h$, in such positions that when the body rests directly on the bolster B said cleats are respectively at the front and rear of said bolster, and thus prevent the body from sliding longitudinally thereon. 75

Inasmuch as the bolsters of different wagons vary in width, the spaces between the cleats $h h$ on the bodies of said wagons likewise differ in width. These variations often occasion much inconvenience in fitting between the said cleats the body-supporting bar with which the bolster-spring is placed on the market. To obviate this defect I make 80 the bar C sufficiently narrow to allow it to enter between cleats $h h$, placed a minimum distance apart, and in order to provide it with proper bearings on the under side of the body, so as to prevent said bar from tilting, I 85 secure to the under side of each end of the bar a metallic shoe or plate, P, which is formed with ears $e e$, by which it embraces the front and rear of the usual stake, t, and also with supporting brackets $f f$, projecting from the 90 front and rear of the plate and bearing against the under side of the body. Said plate I also utilize for bearings for the upper ends of the coil-springs D D by providing said plate with holes for the passage of bolts $l l$ at opposite 95 sides of the longitudinal central line of the plate and forming the under side of the plate 100

with sockets *i i* for the reception of the eyes *c c* of the springs. The bolts *l l*, passing vertically through said eyes and through the plate *P* and bar *C* at the points specified, 5 firmly unite said parts and afford for the springs bearings near the edges of the bar *C*, and thus properly support the same.

Having described my invention, what I claim as new, and desire to secure by Letters Patent, 10 is—

1. In combination with the bolster *B* and bar *C*, two separate coil-springs disposed axially vertically at opposite sides of the bolster and formed individually with bearings at opposite ends.
- 15 2. In combination with the bolster *B* and bar *C*, the coils *D D*, disposed axially vertically at

opposite sides of the bolster, separate from each other, and supported on the bolster, and formed individually at their upper ends with eyes *c c*, 20 disposed with their planes horizontally, and the plate *P*, provided with bolt-holes at opposite sides of its longitudinal central line and formed with sockets *i i* for the eyes *c c* of the coils, substantially as described and shown. 25

In testimony whereof I have hereunto signed my name, in the presence of two witnesses, at Rochester, in the county of Monroe, in the State of New York, this 18th day of May, 1888.

EDWARD CLIFF. [L. S.]

Witnesses:

JAMES J. ALLEN,
C. D. KIEHEL.
